HYMEN A. BLANCHARD, BUFFALO, NEW YORK

CONCRETE CURBING

Application filed February 15, 1928. Serial No. 254,544.

This invention relates to improvements in precast concrete curb sections which are intended to be laid end to end and interlocked with a backing composed of a hard-setting 5 plastic material such as concrete.

The principal object is to provide a curb section, the form of which permits the section to be easily and quickly placed in position against a plastic backing and insures an 10 effective and frost-proof union with the backing when the latter has set without requiring the use of mechanical interlocking forms or attachments.

A further object is to provide a section 15 which while strong and durable may be readily and inexpensively manufactured.

Heretofore it has been proposed to provide curb sections which are so constructed as to have a positive interlock with the plastic 20 backing of cement, concrete or the like, this feature involving a tongue and groove relation of special form which entails serious additional manufacturing expense and complication. While such feature may effectively 25 prevent any upward movement or displacement of the section, it does not certainly prevent an outward or separating displacement inasmuch as it is practically impossible to obtain an intimate union between the 30 smooth surfaced section and the backing and such union as may be obtained depends on the form of the cooperating tongue and groove and is limited to these areas. The collection and freezing of moisture between 35 the curb and backing may thus subject the curb sections to outward displacement or other destructive effects.

The present invention consists mainly in 40 providing a section having throughout the whole or the major area of its rear face a series of adjoining projections and depressions delimited thereby and having roughened faces, these projections and depressions being of such degree and extent that their 45 roughened faces present sensible gripping areas for cooperation with the cement backing. These projections and depressions are preferably provided by roughening the rear face of the section in simulation of the 50 chipped face of a building rock. A face of

this character unites so intimately with the backing as to secure the section against displacement in any direction whatever and to form a union which is absolutely frost or moisture proof. At the same time the section may be manufactured substantially as 55 cheaply as an ordinary section, the gripping face effect being produced by molding or casting.

An embodiment of the invention is illustrated in the accompanying drawings, 60 wherein:

Figure 1 is a perspective view of the rear 65 of one of the curb sections.

Figure 2 is a cross sectional view of the 70 curb as it appears when set in place.

The sections as 1, are cast or molded in such 75 dimensions or cross sectional form as may be desired. The rear face of each section is formed to have an upper smooth surface 2 and a lower roughened surface 3 of special 80 form, the latter being of greater extent than the former. The surface 3 is characterized by the adjoining projections and depressions above described. These may be of regular 85 form and arrangement or they may be of irregular form and arrangement. In any case their faces are rough so as to present a multiplicity of gripping points distributed over sensible angularly extending areas. As 90 shown and preferred the surface 3 simulates the surface of a rough building rock, that is to say, it is formed with a multiplicity of elevated and depressed portions or irregular form and arrangement and rough finish. 95 The very nature of the gripping portion provides a clear line of demarcation between the smooth surface 2 and the rough surface 3 and this line is preferably made substantially straight and parallel with the top of the curb 100 section to facilitate inspection. The simplicity of the form of the section as a whole, facilitates the molding operation and enables the sections to be manufactured quickly and at a low cost.

The curb sections are set upon a plastic bed 105 of concrete as 4 and are held in place by a hard-setting plastic backing, 5, the upper surface of which is preferably sloped as shown. The sections 1 are placed upright on 110

the bed 4 with their roughened surface 3 in intimate contact throughout its extent, with the backing 5 and this position maintained while the concrete of the bed and backing is allowed to set. After the concrete has set and has been inspected, a dirt filling may be placed over the backing or a concrete sidewalk laid in place as shown.

In this manner an effective union is obtained between the parts. The surface 3 for the purpose of its effective union with the backing 5 does not require any undercutting or positive interlocking with said backing inasmuch as notwithstanding the absence of a positive interlock the union formed is so firm as to prevent displacement in any direction and so intimate as to render the same moisture-proof. The union is further insured against the access of moisture by the provision of the sloped upper surface of the extension 5 which functions to drain away any moisture that seeps along the rear of the smooth portion 2 of the section.

In this class of work, the vertical extent of the backing is generally specified, and to facilitate the inspection of the work the rough surface 3 is preferably made of an extent such that it will correspond to the specified extent of the backing in each particular case. Thus when the work is completed, the backing will extend up to the line of demarcation between the smooth surface 2 and the rough surface 3 only if the backing is of the specified extent. As a result of this feature, the inspector is not required to measure the backing but may determine if it is of the proper extent by a mere glance at the completed work.

Having described my invention, I claim:

A precast curb section adapted to be united with a hard setting plastic backing of specified vertical extent comprising a body formed of concrete and having its rear face formed with an upper smooth surface and a lower rough surface, the latter being characterized by adjoining projections and depressions delimited thereby and being of the same vertical extent as the backing, said upper and lower surfaces providing a line of demarcation which marks the upper and lower limit of the rough surface whereby when the rough surface is placed in contact with the backing, the latter will extend at least up to said line of demarcation, the said backing being sloped downwardly away from its front upper edge in order to drain away any water that might seep past the smooth portion of the curb section.

In testimony whereof I hereby affix my signature.

HYMEN A. BLANCHARD.
